UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM BOILER.

Original application filed November 4, 1915, Serial No. 59,503. Divided and this application filed June 9, 1919. Serial No. 302,728.

To all whom it may concern:

Be it known that I, DAVID S. JACOBUS, a citizen of the United States, residing at Jersey City, in the county of Hudson and State of New Jersey, have invented a new and useful Improvement in Steam Boilers, of which the following is a full, clear, and exact description, reference being had to the accompanying drawings, forming part of this 10 specification.

My invention relates to steam boilers of the water tube type.

One of the objects of my invention is the provision of a furnace having an underfeed 15 stoker and an upwardly increasing flow area inclined water tubes being located above the furnace chamber, whereby the gases are thoroughly mingled before contacting with the water tubes.

20 Other objects of my invention will appear in the specification, and will be particularly pointed out in the claims.

My present application is a division of my prior application Serial No. 59,503 which 25 was filed in the United States Patent Office on or about November 4, 1915, Patent No. 1,365,321, issued January 11, 1921.

In the drawings, Figure 1 is a sectional side elevation showing a Babcock & Wilcox 30 boiler and underfeed stoker constructed in accordance with my invention, and Fig. 2 is a sectional front view, with parts broken away of two boilers in a battery setting, the section being on the line 2—2 of Fig. 1.

35 In these drawings, 2 represents the underfeed stoker, which may be of any usual commercial type, and is preferably set further beneath the boiler than in ordinary practice.

The front and rear walls 3 and 4 of the 40 furnace diverge upwardly, each preferably being inclined upwardly and outwardly on the inner faces as illustrated and the outer face of the front wall being inclined outwardly also, the inclined portion of the front 45 wall being supported on a member 3' located at the front thereof. The front wall leans against an exterior support, such as the boiler casing, as shown. This construction of the front and rear walls avoids the tendency 50 before had of leaning or bulging inwardly during use. Furthermore, this arrangement of the front and rear walls increases the mingling effect of the gases and promotes the

combustion thereof, as will be more fully 55 hereinafter explained. By inclining the front wall as described, the coal supply hopper of the stoker is located beneath the uppermost ends of the boiler tubes.

In connection with the underfeed stoker, I 60 employ water-boxes at the sides of the furnace around the stoker grate, these boxes being connected to the boiler circulation. The side water-boxes 5 are preferably inclined rearwardly and downwardly along the side 65 furnace walls. These boxes may extend through the rear wall of the furnace chamber, and their rear ends are connected by bent tubes or pipes 6 to the boiler mud drum 7. The front ends of these side boxes are 70 nipped to the front cross-box 8, extending across the front of the furnace chamber above the grate, and from the box 8 the water flows upward through a number of tubes 9 into the lower part of the front boiler headers 10.

The rear cross-water-box 11 is preferably 75 located below the level of the front cross-box 8 and at the rear of the dumping plate 2' of the stoker, and is partially imbedded in the 80 rear furnace wall, this box being connected by pipes 12 extending through this wall and up to the boiler mud drum 7. From this rear water-box 11 the water flows upwardly 85 through the pipe 13, which is curved upwardly and forwardly at the side of the furnace, into the lower part of the front boiler headers 10.

It will be noted that the downtake and inlet water pipes for the furnace water-boxes 90 are located in a relatively cool portion of the setting, whereas the uptake water pipes for these boxes are subjected to the radiant heat of the fire and to the hot furnace gases, thus causing an efficient circulation through these 95 boxes. Instead of connecting the pipes 6 and 12 to the mud drum they may be connected to the lowermost portion of the rear headers 14 of the boiler if desired.

Blow-off connections 16 are provided for 100 blowing out any mud which may accumulate in the side boxes 5, and blow-off connections 17 are also provided for blowing out any mud which may accumulate in the cross-boxes 11.

The boiler shown is of the usual Babcock & Wilcox type, having a longitudinal steam and water drum 18 connected to the front 105

- and rear headers 10 and 14. The bank of the water tubes 19 is preferably inclined rearwardly and downwardly between the headers, and the baffles 20 and 21 for the boiler tubes are preferably arranged as shown, so that the first upward pass is gradually narrowed upwardly and the second downward pass is narrowed downwardly. A superheater is shown at 22, over which the gases flow directly upward along the inner face of the vertical rear wall of the furnace and would not be effectively mingled with the furnace gases so as to consume the combustible elements in the furnace gases. By 70 inclining the outer face of the front wall, space for standard stoker parts is provided, without losing any of the benefits arising from the inclined inner face of the wall or necessitating special stoker construction. 75
- It will be apparent that the furnace is so formed as to give a progressively increasing area for the flow of gases of combustion in traveling from the fuel bed to the upper part of the furnace, and that the gases pass 80 over a progressively decreasing area in their passage across the first pass of the boiler tubes. The area for admitting the gases into the lower part of the first pass may, therefore, be made large enough to avoid 85 trouble through coating the tubes with slag and deposit to an extent that will result in an excessive frictional resistance to the flow of the gases through the lowermost tubes of the first pass. This feature is a highly essential one where forced blast underfeed 90 stokers of the type described are employed, as with these classes of stokers an undue amount of frictional resistance to the flow of the gases through the boiler tubes will 95 result in a back pressure of the hot gases within the furnace instead of a suction, and a back pressure will cause trouble in maintaining the brickwork, as well as trouble 100 through leaking of the hot gases outward through the doors ordinarily provided for inspection and access to the furnace, as well as through any cracks or crevices in the brickwork. The entire furnace arrangement, as also the arrangement of the baffle, 105 is, therefore, particularly adapted to the form of stoker described, and makes it possible to operate the boilers efficiently at high capacities. 110
- It is especially advantageous in the case 115 of an underfeed stoker to set the stoker further beneath the boiler than in ordinary practice and to incline the front wall outwardly in the way described, as in addition to increasing the mingling effect of the gases and thereby promoting combustion, the erosion of the front wall through the action of the hot gases, which is characteristic of this type of stoker, will be minimized, or eliminated. The erosion referred 120 to comes through the impinging action of the hot gases and through the swirling or vortex action of the gases produced through the effect of the forced blast which enters 125 through the tuyères near the front of the furnace and the form of the fuel bed resulting from the underfeed method of supplying the coal, which causes the depth of the fuel bed to be greater a short distance 130 from the front wall than it is directly
- 10 pass, between the first and second passes through the tubes. The gases finally rise through the third pass and pass out through the damper opening 23, a horizontally-inclined baffle 25 extending from the top of the rear wall 4 to the lower end of the baffle 20 for projecting gases in the rear portion of the combustion chamber forwardly. A dust pocket 24 is preferably provided below the third pass. 15
- 20 The advantages of my invention will be apparent to those skilled in the art. The excess air from below the grate passes upwardly through the dumping plates 2* at the rear of the stoker, flows up at the rear of the furnace and is thrown forward by the roof baffling around the lower row of tubes below the second pass and caused to mingle with the gases from the front of the stoker, thus giving highly efficient combustion. 25
- 30 The arrangement is particularly adaptable to an underfeed stoker where excess air, under certain conditions of operation, passes through the rear part of the stoker mechanism, and through the dumping plates, and 35 is projected rearwardly in the furnace. The form of the tuyères of the stoker which admit the compressed air is such that when the rear portion of the fire becomes thin, or when a portion of the fire is broken through 40 by the action of the blast, the air and gases are projected rearward. It can be readily seen that where a stoker produces an action of this sort the form of furnace is particularly adapted to give increased efficiency 45 over an arrangement wherein the excess air and gases, projected to the rear of the furnace, would pass directly upward along the rear wall of the furnace and enter the spaces between the boiler tubes without being mingled with the combustible gases in the interior of the furnace. 50
- 55 Inclining the rear furnace wall 4 outwardly allows a longer roof baffle 25 to be used, and increases the mingling effect produced in the gases which pass upward in the rear of the furnace. The roof baffling 25 contacts with the cross-baffle 20 in securing a high efficiency, and better results are secured than should the stoker be moved bodily for- 60 ward and the rear wall 4 be made to run vertical, starting directly from a point below the cross-baffle 20, as in the latter case the air and excess gases which pass upward through the stoker dumping plates 2* and through 65 the lowermost tuyères of the stoker would

against and near the front wall. With a vertical front wall the combustion conditions may be such as to cause a lane of flame and unconsumed gases to pass upwardly along the wall and into the spaces between the boiler tubes before the gases are consumed in the furnace, and at the same time there may be difficulty through the erosion of the inner face of the wall through the impinging action of the hot gases or through the swirling of vortex action. By inclining the front wall outwardly the difficulties referred to are minimized or entirely overcome. Under the same conditions, the use of a vertical front wall would lead to a lane of flame hugging the wall, while the use of an inclined front wall of the character illustrated herein, would cause the flame to be spread out and broken up through eddy currents before it reached the tubes, with a resulting increase in the amount of combustible gases burned within the furnace chamber. By reducing the swirling and vortex action of the gases through the use of an inclined wall, where the face of the wall will be at a greater distance from the point from which the hot gases are projected from the fuel bed than with a vertical wall, the amount of erosion will be greatly decreased over that which would exist with a vertical wall. Inclining the rear wall outwardly also increases the mingling effect of the gases in the case of underfeed stokers, so that the form of furnace described is particularly adaptable to underfeed stokers.

With the device illustrated, when the gases pass into the water tubes, they enter what is, in effect, the gas outlet of the furnace, which is directly above the fuel bed; so that the gases pass in a generally vertical direction from the fuel bed. If the fuel bed were close to the water tubes, and hence close to the gas outlet, there would be no chance for the gases to mingle thoroughly and be completely burned before reaching the tubes. Applicant prefers to make the furnace chamber high enough so that the gases will be thoroughly mingled and substantially burned before striking the relatively cold water tubes. This increased height of the furnace introduces a new factor—viz, the swirling or vortex action of the gases which causes erosion of the front wall. To overcome this difficulty and, at the same time, have a relatively high combustion chamber, applicant uniformly inclines the front wall and supports it by a member located in front thereof, thereby, at the same time, minimizing the tendency to erosion and overcoming the tendency of the wall to fall inwardly should erosion take place. Furthermore, inclining the front wall, and preferably also the rear wall to

produce a hopper-shaped furnace, in itself serves to increase the mingling effect of the gases and helps to bring about the complete burning thereof before reaching the boiler tubes.

What I claim and desire to secure by Letters Patent of the United States is:

1. In a steam boiler, a furnace having an upwardly increasing cross sectional area, horizontally inclined water tubes located above the furnace, and a roof baffle extending longitudinally of the water tubes above the furnace and having at its inner end portion an upwardly extending baffle arranged to provide a pass having an upper restricted portion, whereby an increasing cross sectional area in the furnace is succeeded by an upwardly decreasing cross sectional area in the first upward pass.

2. In a steam boiler, means comprising an upwardly inclined furnace wall for producing a furnace chamber having an upwardly increasing cross sectional area, horizontally inclined water tubes located above the furnace chamber, a roof baffle extending longitudinally of the water tubes above the furnace chamber and having at its inner end portion an upwardly extending baffle arranged to provide a pass having an upper restricted portion, whereby an increasing cross sectional area in the furnace is succeeded by an upwardly decreasing cross sectional area in the first upward pass, and means for cooling said inclined furnace wall.

3. In a steam boiler, means comprising an upwardly and outwardly inclined furnace wall for producing a furnace chamber having an upwardly increasing cross sectional area, horizontally inclined water tubes located above the furnace chamber, a roof baffle extending longitudinally of the water tubes above the furnace chamber and having at its inner end portion an upwardly extending baffle arranged to provide a pass having an upper restricted portion whereby an increasing cross sectional area in the furnace is succeeded by an upwardly decreasing cross sectional area in the first upward pass, and means comprising water tubes located adjacent to said inclined wall for cooling the same.

4. In a steam boiler, a furnace provided with a forced blast under-feed stoker and having an upwardly increasing cross sectional area, horizontally inclined water tubes located above the furnace, and a roof baffle extending longitudinally of the water tubes above the furnace and having at its inner end portion an upwardly extending baffle arranged to provide a pass having an upper restricted portion, whereby an increasing cross sectional area in the furnace is succeeded by an upwardly decreasing cross sectional area in the first upward pass.

5. In combination, a furnace having an unobstructed upwardly enlarging furnace chamber, horizontally inclined water tubes located above the furnace chamber, said furnace chamber being sufficiently high to permit approximately complete combustion of the gases before reaching said tubes, a roof baffle located above the furnace chamber and extending parallel to said tubes, and means defining a constricted first pass across the tubes through which the gases flow, said means including said baffle. 10

6. In combination, a furnace having its front and rear walls upwardly and outwardly inclined to form an unobstructed upwardly increasing flow area in the furnace chamber, horizontally inclined water tubes located above the furnace chamber, said furnace chamber being sufficiently high to permit approximately complete combustion of the gases before reaching said tubes, a roof baffle located above the furnace chamber and extending parallel to said tubes, and means defining a constricted first pass 15 across the tubes through which the gases flow, said means including said baffle. 20

7. In a steam boiler and its furnace, a forced blast underfeed stoker, the furnace walls forming a hopper shaped furnace chamber, parallel horizontally inclined boiler tubes located above said furnace chamber, the said tubes being substantially uniformly spaced apart, said furnace chamber being sufficiently high to permit approximately complete combustion of the gases before reaching the boiler tubes, a roof baffle located above said furnace chamber and parallel to said tubes, and means comprising a baffle extending upwardly from the 25

end of said roof baffle across the tubes and forming a decreasing flow area for the gases. 40

8. In combination, a furnace having an unobstructed upwardly enlarging furnace chamber, fuel feeding mechanism for the furnace which causes heated particles to be carried upwardly through the furnace chamber, horizontally inclined water tubes located above the furnace chamber, said furnace chamber being sufficiently high to permit approximately complete combustion of the gases before reaching said tubes, a roof baffle located above the furnace chamber and extending parallel to said tubes, and means defining a constricted first pass 45 across the tubes through which the gases flow, said means including said baffle. 50

9. In combination, a furnace having an unobstructed upwardly enlarging furnace chamber, horizontally inclined water tubes located above the furnace chamber, said furnace chamber being sufficiently high to permit approximately complete combustion of the gases before reaching said tubes, a roof baffle located above the furnace chamber and extending parallel to said tubes, and means defining a constricted first pass 55 across the tubes through which the gases flow, said means including said baffle. 60

10. In testimony whereof, I have hereunto signed my name in the presence of two subscribing witnesses. 70
